Des. 173,633
Patented Dec. 7, 1954

173,633

COMBINED DEODORANT AND TOILET PAPER

ROLL HOLDER

John Wanderer, Los Angeles, Calif.

Application December 18, 1953, Serial No. 28,125

Term of patent 3½ years

(Cl. D4—3)

To all whom it may concern:

Be it known that I, John Wanderer, a citizen of the United States, residing at Los Angeles, in the county of Los Angeles and State of California, have invented a new, original, and ornamental Design for a Combined Deodorant and Toilet Paper Roll Holder, for which the following is a specification, reference being had to the accompanying drawing forming a part hereof.

Fig. 1 is a front elevational view of a combined deodorant and toilet paper roll holder showing my new design;

Fig. 2 is a rear elevational view thereof;
Fig. 3 is a top plan view thereof; and

Fig. 4 is an end elevational view thereof.

I claim:

The ornamental design for a combined deodorant and toilet paper roll holder, as shown.
